[57] ABSTRACT

A system and an apparatus for multiplex transmission of electrical signals via a single signal line. In a transmitter and a receiver, "on" positions of ring counters thereof are sequentially shifted in synchronism with each other by a clock pulse generating circuit and a resetting circuit. Means are provided for converting n electrical signals to output voltages of the respective stages of n -stage ring counter in the transmitter and for sequentially applying said output voltages to the corresponding stages of the read counter in the receiver, through said single signal line, upon every shifting of the "on" position of the ring counter of the transmitter.

SYSTEM FOR MULTIPLEX TRANSMISSION OF ELECTRICAL SIGNALS UTILIZING SYNCHRONIZED RING COUNTERS

This invention relates to multiplex transmission system of electrical signals which permits to transmit multiple simple electrical signals such as voltage signals, logical signals or the like via a single signal wire and to discriminate said signals from each other in a receiver.

Conventionally, there have been provided PCM, PAM, time-division multiplex and frequency-division multiplex systems for transmitting a multiplicity of electrical signals via a reduced number of signal wires. In those systems, however, installation cost was extremely expensive in view of their complicated structure in circuit and mechanisms. Thus, such systems are too expensive to be employed for transmitting simpler electrical signals through short distance, though they might be applicable to a large scale communication system, such as a telephone communication system.

The present invention has been made to solve the above problem and it is therefore an object of the present invention to provide a multiplex transmission system of electrical signals which is composed only of simple circuits and can be manufactured easily and at a low cost.

It is another object of the present invention to provide a multiplex transmission system of electrical signals which permits arbitrary design of circuit depending upon the number of signals to be transmitted and hence permits increase or decrease of circuits, relatively easily according to necessity.

It is a further object of the present invention to provide an apparatus for multiplex transmission of electrical signals which is capable of transmitting voltage corresponding to resistance, voltage corresponding to analog voltage, or the like through simple circuit.

It is a still further object of the present invention to provide an apparatus for multiplex transmission of electrical signals in which n resistance sources whose resistance values are variable selectively by the operation of multipole switches are included in a transmitting station as a signal source, and drive circuit therefor as well as a plurality of loads are connected in a receiving station, whereby connection and disconnection between a set of switches and a set of loads in, for example, automobiles or the like is controlled via a single signal line and a single power supply line.

It is a still further object of the present invention to provide an apparatus for multiplex transmission of electrical signals, which permits arbitrary design of circuit depending upon the number of signals to be transmitted facilitating increase or decrease circuit relatively easily according to necessity.

The present invention will now be described in conjunction with the accompanying drawings illustrating a preferred embodiment of the present invention, in which;

FIG. 1 shows a basic electric circuit,

FIG. 2 shows voltage waveforms at various points in the above circuit,

FIGS. 3 to 6 show circuit diagrams employable for various purposes in combination with the circuit of FIG. 1; wherein FIG. 3 shows an output circuit to be connected with a receiver; FIG. 4 shows an input circuit to be connected to a transmitter; FIG. 5 shows a

switch circuit to be connected to the transmitter and FIG. 6 shows a driver circuit to be connected to the receiver.

Referring first to FIG. 1 which is a basic circuit diagram of the present invention, there is illustrated a transmitter A connected with a receiver B via a single signal line L. The transmitter A comprises a ring counter having n stages $1_1, 1_2, \dots, 1_n$ (n is an integer of two or more), a resetting circuit 2 and a clock pulse generating circuit 3. The receiver B comprises a ring counter having the same number of stages $4_1, 4_2, \dots, 4_n$ as those of the ring counter in the transmitter A.

A first stage 1_1 of the ring counter in the transmitter A is composed of capacitors C_1 and C_{11} , resistors R_1 , R_{11} and R_{21} , a variable resistor VR_1 , a diode D_{11} , a Zener diode ZD_1 , and transistors Tr_{11} and Tr_{21} , and a second stage 1_2 of said ring counter is connected through said capacitor C_{11} . Said second stage 1_2 is composed of a capacitor C_{12} , resistors R_{12}, R_{22}, R_{32} and R_{42} , a variable resistor VR_2 , diodes D_{12} and D_{22} and transistors Tr_{12} and Tr_{22} . Other succeeding stages are similarly constructed but a final stage 1_n is composed of a capacitor C_{1n} , resistors R_{1n}, R_{2n}, R_{3n} and R_{4n} , a variable resistor VR_n , diodes D_{1n} and D_{2n} , and transistors Tr_{1n} and Tr_{2n} . Each stage of the ring counter is coupled with a capacitor of respective preceding stage (for example, a third stage of the ring counter is coupled with the capacitor C_{12} in the second stage 1_2). The capacitor C_{1n} is so selected that it has sufficiently larger capacitance than those of capacitors C_{11}, C_{12} , and C_{1n-1} in the preceding stages.

A resetting circuit 2 comprising resistors R_2 and R_{10} and a transistor Tr_3 is coupled with the final stage 1_n of the ring counter through the capacitor C_{1n} .

Connected to a collector of the transistor Tr_3 in the resetting circuit 2 is a clock pulse generating circuit 3 comprising transistors Tr_4 and Tr_5 , a resistor R_3 and a capacitor C_2 . E designates a power supply, R_4 , R_5 resistors and D_3 a diode, respectively.

In the receiver B, a first stage 4_1 of the ring counter is composed of capacitors C_3 and C_{41} , resistors R_6, R_7, R_{81} and R_{91} , a Zener diode ZD_2 , and transistors Tr_{61} and Tr_{71} , and a second stage 4_2 of said ring counter is coupled therewith via said capacitor C_{41} . Said second stage 4_2 of the ring counter is composed of a capacitor C_{42} , resistors R_{62} and R_{92} , diodes D_{42} and D_{52} , and transistors Tr_{62} and Tr_{72} . The succeeding stages are constructed in similar way but the final stage 4_n , which is composed of resistors R_{8n} and R_{9n} , diodes D_{4n} and D_{5n} and transistors Tr_{6n} and Tr_{7n} . Each stage of the ring counter is connected to a capacitor of the preceding stage, respectively. E_1 designates a power supply and C_{4n-1} represents a capacitor of a stage immediately preceding the final stage 4_n of the ring counter.

The operation of the circuit assembly thus constructed is now described. Pairs of transistors Tr_{11} and Tr_{21} ; Tr_{12} and Tr_{22} . . . Tr_{1n} and Tr_{2n} and Tr_{61} and Tr_{71} ; Tr_{62} and Tr_{72} . . . Tr_{6n} and Tr_{7n} constitute conventional ring counters and they are so designed that when either one of the transistors constituting such a pair is turned on, the other is also turned on by virtue of positive feedback and that when either one of the transistors is turned off, the other is also turned off. Each of said pairs of transistors Tr_{12} and Tr_{22} ; . . . Tr_{1n} and Tr_{2n} and Tr_{62} and Tr_{72} ; . . . Tr_{6n} and Tr_{7n} is adapted to be turned on only when a positive pulse is applied through a capacitor coupled to the respective preceding stages (for

example, a pair of transistors Tr_{12} , Tr_{22} are turned on by a positive pulse applied through the capacitor C_{11} . The transistors Tr_{11} and Tr_{21} and Tr_{61} and Tr_{71} in the first stages 1_1 and 4_1 of the ring counters are supplied with base currents and turned on only when all other transistors are in "off" states.

Assuming that the transistors Tr_{11} and Tr_{21} , and Tr_{61} and Tr_{71} of the first stages 1_1 and 4_1 of the ring counters are now in their "on" states, an emitter current of the transistor Tr_{61} of the first stage of the receiver B flows through the diode D_{11} partially as a collector current of the transistor Tr_{11} in the first stage of the transmitter A. An emitter current of the transistor Tr_{21} is fed through the resistor R_5 , the diode D_3 and the resistor R_4 , but a collector voltage of the transistor Tr_4 in the clock pulse generating circuit 3 is a voltage determined due to resistance division by resistors R_5 and R_4 . As the capacitor C_2 of the clock pulse generating circuit 3 is charged gradually through the resistors R_5 and R_3 and the charged potential, namely, emitter potential of the transistor Tr_5 becomes higher than collector potential of the transistor Tr_4 , the transistor Tr_5 is turned on. This results in feeding of a base current to the transistor Tr_4 , causing it to be turned on. By the action of this positive feedback, the charge of the capacitor C_2 is instantaneously discharged through the transistors Tr_5 and Tr_4 .

When the transistor Tr_4 is turned on, the current flowing through the resistor R_5 and the diode D_3 is fully diverted to the transistor Tr_4 , so that no current flows through the emitter of the transistor Tr_{21} in the first stage 1_1 of the ring counter, which results in turning-off of the transistor Tr_{21} and the transistor Tr_{11} . Since a positive pulse is applied to the capacitor C_{11} simultaneously with turning-off of the transistor Tr_{11} , a current flows through the resistor R_{32} . This current flows to the ground through the diode D_{22} , the resistor R_4 and the transistor Tr_4 when the transistor Tr_4 is in "on" condition, but the current flows through the resistor R_{42} as a base current of the transistor Tr_{12} in the second stage 1_2 of the ring counter when the transistors Tr_4 and Tr_5 are turned off as a result of discharge of the capacitor C_2 .

As a result, the transistor Tr_{12} is turned on and accordingly, the transistor Tr_{22} is also turned on. When the transistors Tr_{12} and Tr_{22} are turned on, voltage potential of a common line L_1 is lowered and the base current of the transistor Tr_{11} is not supplied because it is blocked by the Zener diode ZD_1 . This assures that the transistors Tr_{11} and Tr_{21} are not turned on again. Even if a positive pulse is produced on the common line L_1 during a transient time when the "on" position of the ring counter is shifted from the transistors Tr_{11} and Tr_{21} to the transistors Tr_{12} and Tr_{22} , it will be absorbed by the capacitor C_1 , preventing erroneous turning-on of the transistors Tr_{11} and Tr_{21} .

The discharge of the capacitor C_2 is effected in an instant, so that "on" time of the transistor Tr_4 is very short.

Since the transistors in all stages 1_1 , 1_2 , ..., 1_n of the transmitter A are in "off" condition so long as the transistor Tr_4 has been kept "off", the potential of the signal line L is raised. As a result, emitter current of the transistor Tr_{61} in the first stage 4_1 of the ring counter of the receiver B is blocked and the transistors Tr_{61} and Tr_{71} therein are turned off. Simultaneously with turning-off of the transistor Tr_{61} , a positive pulse is applied

to the capacitor C_{41} and supplied through the diode D_{52} as a base current of the transistor Tr_{62} in the second stage 4_2 of the ring counter.

Thus, the transistor Tr_{12} in the second stage 1_2 of the ring counter of the transmitter A is turned on, so that the potential of the signal line L is lowered and, at the same time, the transistor Tr_{62} in the second stage 4_2 of the ring counter is turned on. When the transistor Tr_{62} is turned on, the emitter current thereof flows through the diode D_{12} partially as a collector current of the transistor Tr_{12} .

It is thus seen that the transistors Tr_{12} and Tr_{22} , and Tr_{62} and Tr_{72} in the second stages 1_2 and 4_2 of the ring counters are now turned on, instead of the transistors

Tr_{11} and Tr_{21} , and Tr_{61} and Tr_{71} , upon instantaneous turning-on of the transistor Tr_4 in the clock pulse generating circuit 3 or upon occurrence of a clock pulse. The transistor Tr_4 produces clock pulses by repeatedly turning on and off at a frequency of a time constant determined by the resistor R_3 and the capacitor C_2 . Thus, if a further clock pulse is produced while the transistors Tr_{12} and Tr_{22} , and Tr_{62} and Tr_{72} of the second stages 1_2 , 4_2 of the ring counters are in "on" condition, a similar operation as mentioned above is effected. Stated illustratively,

Tr_{12} and Tr_{22} , and Tr_{62} and Tr_{72} are turned off and the transistors in third stages (not shown) of the ring counters are turned on. Upon every occurrence of subsequent clock pulses, the "on" positions of the ring counters of the transmitter A and the receiver B are shifted step by step in synchronism with each other.

When a positive pulse is applied to the capacitor C_{1n} of the final stage 1_n of the ring counter, a base current is supplied to the transistor Tr_3 of the reset circuit 2

35 through the resistor R_2 to turn on said transistor Tr_3 . Therefore, all the transistors in the stages 1_1 , 1_2 , ..., 1_n , 4_1 , 4_2 , ..., 4_n of the transmitter A and the receiver B are turned off similarly in case the transistor Tr_4 in the clock pulse generating circuit 3 is turned on. After a 40 time period determined by the time constant of the capacitor C_{1n} and the resistor R_2 , the transistor Tr_3 is turned off. The transistor Tr_{11} whose base current is supplied through the resistor R_3 , the diode D_3 , the resistors R_4 and R_1 and the Zener diode ZD_1 , and the transistor Tr_{61} whose base current is supplied through the resistors R_6 and R_7 and the Zener diode ZD_2 , are then turned on simultaneously, whereby the transistors Tr_{61} and Tr_{71} are also turned on, restoring the apparatus into the original condition. Thus, similar operation is 50 repeatedly performed.

At the starting of the apparatus, if the transistors Tr_{12} and Tr_{22} in the second stage 1_2 of the ring counter of the transmitter A are in "on" condition and the transistors Tr_{61} and Tr_{71} in the first stage 4_1 of the ring counter of the receiver B are in "on" position, in the transmitter A, the transistors in the third stage of the ring counter and in the receiver B, the transistors Tr_{62} and Tr_{72} in the second stage 4_2 of the ring counter are turned on upon the occurrence of the next clock pulse. Similarly, the 60 "on" positions of the ring counters are shifted step by step until the transistors Tr_{1n} and Tr_{2n} in the final stage 1_n of the transmitter A, and the transistors in the stage immediately preceding the final stage 4_n of the ring counter in the receiver B are turned on. In this condition, if a clock pulse is produced, the transistors Tr_{1n} and Tr_{2n} and the transistors in the stage immediately preceding the final stage 4_n of the receiver B are turned

65

off. With these transistors turned off, the transistor Tr_3 in the resetting circuit 2 is turned on. The transistor Tr_{6n} tends to be turned on by a base current supplied from the capacitor C_{4n-1} but it is kept in "off" condition so long as the transistor Tr_3 is turned on. By selecting the time constant determined by the capacitor C_{1n} and the resistor R_2 substantially larger than the time constant determined by the capacitor C_{4n-1} and the resistor R_{9n} , the charge of the capacitor C_{4n-1} will complete its discharge through the diode D_{5n} and the resistor R_{8n} while the transistor Tr_3 is in "on" condition, so that the transistor Tr_{6n} in the final stage 4_n of the ring counter will no longer be turned on.

It is thus seen that it is the transistors Tr_{11} , Tr_{21} and Tr_{61} , Tr_{71} in the first stages 1_1 and 4_1 of ring counters of both the transmitter A and the receiver B that are to be turned on when the transistor Tr_3 is deenergized again.

Though the foregoing description is given concerning the operation which is started under the condition that in the transmitter A, the transistors Tr_{12} and Tr_{22} in the second stage 1_2 of the ring counter are turned on and in the receiver B, the transistors Tr_{61} and Tr_{71} in the first stage 4_1 of the ring counter are turned on, similar operations can be seen in other cases. Stated illustratively, in case transistors in other stages of the ring counters are randomly in "on" condition at the starting time of the operation, or in case some transistors are randomly turned on, during the operation, due to some possible noise, the "on" positions of the ring counters are sequentially shifted until the transistors Tr_{1n} and Tr_{2n} in the last stage 1_n of the transmitter A are turned on and turned off again thereafter to energize the transistor Tr_3 in the resetting circuit 2. All transistors other than the transistors Tr_{11} and Tr_{21} , and Tr_{61} and Tr_{71} in the first stages of the ring counters are kept in "off" condition, whatever the condition of the ring counters may be immediately before such turning-on of the transistor Tr_3 , if the turning-on period of time of said transistor Tr_3 is sufficiently long. Accordingly, when the transistor Tr_3 is then deenergized, the transistors Tr_{11} and Tr_{21} , and Tr_{61} and Tr_{71} are necessarily turned on, thereafter permitting sequential shifting of "on" positions of the ring counters in synchronism with each other.

Signal transmission will now be described. When the transistors Tr_{11} and Tr_{21} , Tr_{61} and Tr_{71} of the first stages 1_1 and 4_1 of the ring counters of the transmitter A and the receiver B are in "on" condition and fully saturated and if the value of the resistor R_{81} is chosen substantially larger than that of the resistor R_{11} , the collector voltage of the transistor Tr_{11} will be determined through voltage division by the resistor R_{11} and the variable resistor VR_1 . On the other hand, since the transistor Tr_{61} is also turned on, the collector voltage of the transistor Tr_{61} is the sum of the collector voltage of the transistor Tr_{11} and a threshold voltage of the diode D_{11} . Therefore, the collector voltage of the transistor Tr_{61} will be proportional to the resistance value of the variable resistor VR_1 . In other words, the output voltage of the receiver B is proportional to the resistance value of the variable resistor VR_1 of the transmitter A.

A similar effect can be seen in the second stage 4_2 of the ring counter in the receiver B. Stated illustratively, the collector voltage of the transistor Tr_{62} is proportional to the resistance value of the variable resistor

VR_2 when the transistor Tr_{12} of the second stage 1_2 of the ring counter of the transmitter A are in "on" condition. Similarly, the output voltage in each stage of the ring counter in the receiver B is proportional to the resistance value of the variable resistor in the same stage of the transmitter A. With the circuit illustrated, transmittable voltage value is in the order of one third of the power supply voltage.

The embodiment described above will now be explained more particularly with reference to FIG. 2 which shows voltage waveforms at various points in the circuits. Assuming that the voltage of the power supply E of the transmitter A is 10V, resistance values of the resistors R_{11} , R_{12} , ... and R_{1n} are $1K\Omega$, resistance value of the variable resistor VR_1 is 200Ω , resistance value of the VR_2 is 0Ω and resistance value of the VR_n is 100Ω , then the voltage waveform as shown in FIG. 2a appears on the signal line L. The pulse P_1 is a resetting pulse produced when the transistor Tr_3 of the resetting circuit 2 is turned on, V_1 is a voltage appearing on the signal line L when the first stage 1_1 of the ring counter is turned on. Similarly, V_2 , V_n are voltages appearing on the signal line L when the second stage 1_2 and the final stage 1_n are in "on" conditions, respectively. P_2 , P_3 and P_n are clock pulses appearing on the signal line L whenever the transistor Tr_4 of the clock pulse generator B is turned on. FIG. 2b shows a collector voltage waveform of the transistor Tr_{62} in the first stage 4_1 of the ring counter of the receiver B. The low voltage level thereof is at 2.3V which is the sum of 1.7V determined through resistor division by the resistor R_{11} and the variable resistor VR_1 in the first stage 1_1 of the transmitter A, and 0.6 V of threshold voltage of the diode D_{11} . The high voltage level thereof is at 10V of the power supply voltage, which shows the transistor Tr_{61} is in "off" state.

FIG. 2c shows collector voltage waveform of the transistor Tr_{62} in the second stage 4_2 of the ring counter of the receiver B. The low voltage level is at 0.6V which corresponds to threshold voltage of the diode D_{12} because the emitter of the transistor Tr_{12} in the second stage 1_2 of the ring counter of the transmitter A is grounded. The high voltage level is at 10V of the power supply voltage as in the previous case.

FIG. 2d shows collector voltage waveform of the transistor Tr_{6n} in the final stage 4_n of the ring counter of the receiver B. The low voltage level is at 1.5V which is the sum of 0.9V of resistance division value of the resistor R_{1n} and the variable resistor VR_n in the final stage 1_n of the transmitter A and 0.6V of the threshold voltage of the diode D_{1n} . The high voltage level is at 10V of the power supply voltage.

As has been described above, voltage pulses the magnitudes of which are proportional to the resistance values of the variable resistors VR_1 , VR_2 , ... and VR_n connected to the respective stages 1_1 , 1_2 , ... and 1_n of the ring counter of the transmitter A appear at respective outputs of the stages 4_1 , 4_2 , ... 4_n of the ring counter of the receiver B. Application examples of the present invention will be given in the following.

One application example in which temperature is collectively detected is first explained. A thermistor is connected in place of the variable resistor VR_1 , VR_2 , ... VR_n in respective stage 1_1 , 1_2 , ... 1_n of the ring counter of the transmitter A, and a cathode of a diode D_{111} in the circuit shown in FIG. 3 is connected to each of the collectors of the transistors Tr_{61} , Tr_{62} , ... Tr_{6n} of the stages 4_1 , 4_2 , ... 4_n of the receiver B. An output cir-

cuit including the diode D_{111} is composed of a transistor Tr_{111} , resistors R_{111} and R_{112} , and a capacitor C_{111} . If the time constant determined by the resistor R_{111} and the capacitor C_{111} is chosen sufficiently longer than the period of the ring counter, the base voltage of the transistor Tr_{111} depends upon a low level of cathode potential of the diode D_{111} or the signal voltage. Accordingly, by installing thermistors at positions where detection of temperature is desired, the temperature at those positions may be detected as output voltage of the output transistor Tr_{111} of each stage in the receiver B.

With the above-mentioned circuit arrangement, heat generation of a number of motors or the like in a factory or the like may be collectively monitored and accident due to possible overheating of the motor can be well prevented.

Another application example in which analogue voltages are transmitted will be described hereunder. An emitter of a transistor Tr_{121} of a circuit shown in FIG. 4 is connected in place of variable resistors VR_1 , VR_2 , ... VR_n in the stages 1_1 , 1_2 , ... 1_n of the ring counter of the transmitter A. A resistor R_{121} is connected between the emitter of the transistor Tr_{121} and the ground. By making the emitter currents of the transistors Tr_{11} , Tr_{12} , ... Tr_{1n} and the resistance of the resistor R_{121} sufficiently small, the emitter voltage of the transistor Tr_{121} is a difference between a signal voltage applied to the base of the transistor Tr_{121} and the voltage across the base and emitter of the transistor Tr_{121} , irrespective of a current from the ring counter. This voltage is transmitted through the signal line L to collectors of the transistors Tr_{61} , Tr_{62} , ... Tr_{6n} of the ring counter stages 4_1 , 4_2 , ... 4_n of the receiver B. Thus, by connecting the cathode of the diode D_{111} of the circuit shown in FIG. 3 to respective collector of the transistors Tr_{61} , Tr_{62} , ... Tr_{6n} , the voltage proportional to the respective signal voltage applied to the base of the transistor Tr_{121} connected to the respective stage of the ring counter of the transmitter A appears at the output of the transistor Tr_{111} .

With the circuit arrangement described above, it is possible to collectively monitor pulsations per unit time period of a number of patients with advanced diseases in a hospital by converting the pulsations to voltages, whereby early detection of an abnormal patient is assured.

Other application example in which a number of loads (such as relays) are remotely controlled is explained hereinbelow. A movable contact of three-contact switch S in the circuit shown in FIG. 5 is connected in place of each of the variable resistors VR_1 , VR_2 , ... VR_n in the stages 1_1 , 1_2 , ... 1_n of the ring counter of the transmitter A. Between fixed contacts of the switch S and the ground, a first fixed contact S_1 is directed grounded, a second fixed contact S_2 is grounded via a resistor R_{131} , and a third fixed contact S_3 is grounded via a resistor R_{132} . To a cathode of a diode D_{141} of the circuit shown in FIG. 6 is connected each of the collectors Tr_{61} , Tr_{62} , ... Tr_{6n} of the stages 4_1 , 4_2 , ... 4_n of the ring counter of the receiver B. A drive circuit including the diode D_{141} is composed of transistors Tr_{141} to Tr_{143} , resistors R_{141} to R_{145} , capacitors C_{141} to C_{143} , diodes D_{142} to D_{150} and relays Y_1 and Y_2 .

For the purpose of clarification of the description, explanation is directed to the first stages of the transmitter A and the receiver B, and it is assumed that the

resistor R_{131} is of 200Ω , R_{132} is of 100Ω , R_{11} is of $1K\Omega$, R_{31} is of $10K\Omega$ and the power supply voltage is 10V.

When the movable contact of the switch S is placed to a position of the first fixed contact S_1 , the emitter of the transistor Tr_{11} is directly grounded so that the collector voltage of the transistor Tr_{61} is 0.6V of the low level as shown in FIG. 2c, which is seen from the description of the circuit of FIG. 1. Thus when the cathode voltage of the diode D_{141} of the driver circuit is 0.6V of the low level, the charge in the capacitor C_{141} is almost fully discharged through the diode D_{141} and the transistor Tr_{141} is deenergized. If the time constant of the resistor R_{141} and the capacitor C_{141} is sufficiently large, the current flowing through the resistor R_{141} charges the capacitor C_{141} even if the cathode potential of the diode D_{141} increases to the high level corresponding to the power supply voltage. Thus, the transistor Tr_{141} remains in its "off" state without turning on. When the cathode potential of the diode D_{141} becomes 20 the low level, the charge in the capacitor C_{141} is discharged through the diode D_{141} so that no base current flows into the transistor Tr_{141} , keeping it in its "off" state. With the transistor Tr_{141} being always in its "off" state, the base current of the transistor Tr_{142} is supplied 25 via the diode D_{145} , so that the transistor Tr_{142} is turned on. Thus, the relay Y_1 is actuated and the load connected to the contacts of the relay Y_1 may be controlled. On the other hand, since the base current of the transistor Tr_{143} is blocked by the capacitor C_{142} , said 30 transistor Tr_{143} is not turned on and the relay Y_2 is not actuated.

When the movable contact of the switch S is connected to the second fixed contact S_2 , the emitter of the transistor Tr_{11} is connected to the ground through 35 200Ω of emitter resistor R_{131} , so that the collector voltage of the transistor Tr_{61} is at 2.3V of the low level as shown in FIG. 2b, which is seen from the description of the circuit of FIG. 1. In order to turn off the transistor Tr_{141} , the base potential thereof must be below 2.4V 40 which is the sum of the threshold voltages ($3 \times 0.6V$) of the diodes D_{142} , D_{143} and D_{144} and 0.6V of threshold voltage of the transistor Tr_{141} . Therefore, unless the cathode potential of the diode D_{141} is below 1.8V, which is a difference between 2.4V and 0.6V of threshold voltage of the diode D_{141} , the transistor Tr_{141} will not be turned off. Therefore, under the conditions, the current supplied through the resistor R_{141} flows into the base of the transistor Tr_{141} , keeping said transistor Tr_{141} in "on" condition. Accordingly, no current is supplied 45 to the bases of the transistors Tr_{142} and Tr_{143} and they remain in their "off" states. The relays Y_1 , Y_2 are, therefore, not actuated.

When the movable contact of the switch S is connected to the third fixed contact S_3 , the emitter of the transistor Tr_{11} is grounded via 100Ω of the resistor R_{132} , so that the collector voltage of the transistor Tr_{61} is at 1.5V of the low level as shown in FIG. 2d. When the cathode potential of the diode D_{141} is at 1.5V of the low level, the charge in the capacitor C_{141} is discharged until the voltage at anode side reaches about 2.1V, when the transistor Tr_{141} is turned off. Since the voltage at anode side of the capacitor C_{141} is sufficiently high as compared with the case where the movable contact is connected to the first fixed contact S_1 , the capacitor C_{141} is charged through the resistor R_{141} when the cathode potential of the diode D_{141} becomes high level corresponding to the power supply voltage. The time pe-

riod required to reach the voltage enough to turn on the transistor Tr_{141} is sufficiently shorter as compared with the case where the movable contact is connected to the first fixed contact S_1 .

Therefore, before the cathode potential of the diode D_{141} has been reduced to the low level again, the transistor Tr_{141} is turned on. Thereafter, when the cathode potential of the diode D_{141} is lowered to the low level, the transistor Tr_{141} is turned off. Thus, the transistor Tr_{141} repeats its "on" and "off" states, whereby the base current is supplied to the transistor Tr_{143} through the action of the capacitors C_{142} and C_{143} and the diodes D_{149} and D_{150} which constitute a D.C. restoration and an integration circuit, keeping said transistor Tr_{143} in its "on" state. The relay Y_2 is accordingly driven and the load connected to the contact thereof may be controlled.

With the transistor Tr_{143} kept in its "on" state, the current supplied through the resistors R_{142} and R_{143} when the transistor Tr_{141} is in its "off" state, flows mostly through the diode D_{142} and the transistor Tr_{143} , so that the transistor Tr_{142} is kept in its "off" state. The relay Y_1 is, therefore, not actuated.

The circuit arrangement described above can be employed in an automobile with great advantages, where wiring is extremely complicated for connecting various kinds of switches to various loads. Stated illustratively, with such a circuit arrangement, the switches can be coupled with the loads through a single signal line and a single power line. Accordingly, wiring work in manufacturing process is much simplified, possible miswiring is well avoided and risk of wire breakage or shortcircuit is by far reduced.

In the embodiments of FIGS. 5 and 6 as mentioned above, the first stages 1_1 and 4_1 of the ring counters were explained particularly. However, it should be understood that by connecting the switch of FIG. 5 and the driver circuit of FIG. 6 to each of the second to n -th stages, $2n$ relays can be controlled by n stages.

It should also be understood that ring counters using flip-flop, SCR or the like may be employed in place of the ring counters used in the embodiment of FIG. 1, for the same purpose.

As has been fully described hereinabove, the present invention is characterized by the transmitter comprising the n -stage ring counter, the clock pulse generating circuit and the resetting circuit, and the receiver comprising the ring counter, the transmitter and the receiver being coupled through a single signal line, "on" positions of the ring counters in the transmitter and the receiver being sequentially shifted with the clock pulses supplied by the clock pulse generating circuit and both ring counters being synchronized with respect to their "on" positions by reset pulse from the resetting circuit. In this way, an output of each stage of the transmitter is transmitted to a corresponding stage of the receiver, permitting multiplex transmission of a multiple of signals through a single signal line. Since the present system can transmit voltage signals corresponding to resistance values or voltage signals corresponding to analogue voltage values, it may be employable for various purposes, such as central monitoring of temperature, detection of analogue values in which a number of parameters change continuously, and separate control for a number of loads. The number of stages of the ring counter may be selected arbitrarily depending upon the number of signals to be transmitted. Furthermore,

since only simple circuits are used in the present apparatus, manufacturing cost is by far reduced as compared with a conventional apparatus for multiplex transmission of electrical signals.

What is claimed is:

1. A multiplex transmission system for electrical signals, comprising in combination:

a transmitter comprising a ring counter having n stages;

a receiver comprising a further ring counter having n stages;

said n transmitter ring counter stages each having electronic switch means for converting a corresponding one of n input electrical signals to an output voltage of the respective stage;

periodic pulse generating means connected to the stages of one said ring counter for sequentially shifting stage activation therein;

a single signal line and means collectively connecting said n transmitter stages to said n receiver stages through said single signal line for shifting stage activation of said other ring counter in synchronism with said shifting in said one ring counter, each of said receiver ring counter stages having electronic switch means connected to said single signal line and responsive to said output voltage of the corresponding transmitter stage for providing an output corresponding to the respective input electrical signal;

to thereby sequentially transmit through a single line the signal inputs to sequentially activated transmitter stages to outputs of correspondingly sequentially actuated receiver stages.

2. The system of claim 1 in which said electronic switch means of each said stage comprises first and second opposite polarity electronic devices coupled in a feedback loop, and including capacitive coupling means between the first electronic devices of adjacent stages for activating one stage in response to deactivation of the preceding stage, said first electronic devices of said receiver stages being connected to said single signal line, said transmitter stages each including unidirectional conducting means for connecting the respective first electronic device thereof to said single signal line.

3. The system of claim 2 in which said periodic pulse generating means include further electronic switch means coupled to said electronic devices of said transmitter stages for deactivating activated ones thereof so as to produce a corresponding pulse on said single signal line.

4. The apparatus of claim 3 in which said electronic switch means of each stage of said transmitter includes means connecting the corresponding input electrical signal in series with said first electronic device and said unidirectional conducting means of said transmitter stage for correspondingly varying the voltage on said single signal line in response to activation of said stage, the corresponding receiver stage having an output terminal associated with the side of the first electronic device thereof opposite that side connected to said single signal line.

5. An apparatus for multiplex transmission of electrical signals, comprising in combination:

a transmitter having an n -stage ring counter, each stage including a source for providing a signal amplitude to be transmitted, a decoupling element

and a first electronic switching means actuatable for serially connecting said source to said decoupling element, each said stage further including a second electronic switching means connected to said first electronic switching means for terminating conduction therethrough;
 a single signal line connected to the decoupling element of each of said stages;
 a receiver having a further n -stage ring counter, each stage including a third electronic switching means and further including a fourth electronic switching means connected to said third electronic switching means for terminating conduction therethrough, each of said third electronic switching means being connected to said signal line for producing an output corresponding to the source signal amplitude of the corresponding transmitter stage and for synchronizing advancement of said receiver and transmitter stages;
 pulse generator means connected commonly to the stages of one of said ring counters for sequentially advancing stage actuation in said one ring counter;

whereby a signal from said source applied to one said first electronic switching means of said transmitter results in a corresponding output signal on the corresponding third electronic switching means of said receiver.

6. An apparatus as claimed in claim 5 in which said first and second electronic switching means are respectively NPN and PNP transistors, said source being connected to the emitter of said NPN transistor, said decoupling elements being respectively connected to the collectors of said NPN transistors of each stage of said transmitter ring counter, said third and fourth electronic switching means being respectively NPN and PNP transistors, the emitters of said NPN transistors of said receiver being each connected to said single signal line, said pulse generating means including a clock-pulse generator and a reset-pulse generator cooperative therewith, said signal from said source in a given transmitter stage being coupled to the emitter of the NPN transistor of said given transmitter stage and appearing as a corresponding collector voltage of the NPN transistor of the corresponding receiver ring counter stage.

7. An apparatus as claimed in claim 6 including variable resistor means in series with respective ones of said NPN transistors of said transmitter and coupled to the emitters thereof, said resistor means being variable in resistance as a measure of a parameter to be transmitted, an output transistor for each receiver stage and unidirectional conducting means coupling an input electrode of said output transistor to the collector of the NPN transistor of the corresponding receiver stage, a time constant circuit connected to said output transistor and having a time constant longer than the period of the receiver ring counter for causing the output voltage of said output transistor to represent the resistance of the variable resistor means of the corresponding transmitter stage.

8. An apparatus as claimed in claim 6 including a signal voltage input transistor for at least one stage of said transmitter ring counter and means coupling the emitter potential of said signal voltage transistor to the first electronic switching means of said stage, the corresponding stage of said receiver ring counter including

means for providing as an output a voltage proportional to the signal voltage applied to said signal voltage input transistor.

9. An apparatus as claimed in claim 6 in which said transmitter ring counter includes, in at least one stage thereof, a multicontact switch having a movable contact coupled to the other side of the corresponding one of said first electronic switching means, said switch having fixed contacts and selected resistances connected thereto for alternative selection by said movable contact, the corresponding stage of said receiver ring counter including first and second relays and respective first and second relay drive transistors in series therewith, an input transistor, unidirectional voltage dropping means coupling the base of said input transistor to the other side of the first electronic switching means of the corresponding receiver ring counter stage, an RC time base network for said input transistor, a voltage divider paralleling said RC network, said input transistor being connected at one side to a point intermediate the ends of said voltage divider and being coupled at the other side thereof to further voltage dropping means, means coupling spaced points on said voltage divider to the bases of said first and second drive transistors for energizing said relays in differing combinations dependent upon the position selected for the movable contact of said switch in said transmitter stage.

10. An apparatus as claimed in claim 5, wherein said pulse generating means includes reset circuit means responsive to completion of operation of the nth transmitter ring counter stage for applying a reset-pulse to said signal line and deenergizing all stages of said transmitter and receiver ring counters except the first stages of each, said pulse generating means further including resetting periodically actuated clock-pulse generating means for sequentially shifting the "on" position of the transmitter ring counter by one stage while applying a clock-pulse to said signal line for synchronously shifting the "on" position of said receiver ring counter by one stage.

11. An apparatus as claimed in claim 5, wherein said sources comprise n electrical resistors coupled in circuit with respective first electronic switching means for causing said respective first electronic switching means to convert n electrical signals appearing across said n electrical resistors to output voltages of respective stages of said transmitter, for sequential application to said signal line.

12. An apparatus as claimed in claim 5, wherein said sources comprise n analogue voltage sources coupled to respective first electronic switching means for causing n electrical signals supplied thereby to be converted by said first electronic switching means to output voltages sequentially appearing on said signal line.

13. An apparatus as claimed in claim 5, in which said sources comprise at least n resistors and multipole switch means associated with said n resistors and switchable for selectively varying the resistance values of said resistors, said receiver including a plurality of relays and driver circuits for said relays connected to outputs of the respective stages of said receiver ring counter, resistance values corresponding to the positions of said switch means being converted to output voltages of the transmitter ring counter, and means connecting said driver circuits for respective stages of said receiver ring counter for driving loads in correspondence to the positions of said switch means.
